UNITED STATES PATENT OFFICE

ANTONIUS DE GRAAFF, OF EINDHOVEN, NETHERLANDS, ASSIGNOR, BY MESNE ASSIGNMENTS, TO GENERAL ELECTRIC COMPANY, OF SCHENECTADY, NEW YORK, A CORPORATION OF NEW YORK

APPARATUS FOR CLEANING WIRE

Application filed June 1, 1922, Serial No. 565,279, and in the Netherlands June 10, 1921.

This invention relates to the cleaning of wire and more especially of wire used as filaments or supports in incandescent electric lamps.

5 When drawing wire for incandescent lamps, it is customary to use a lubricant containing carbon and unless the wire is cleaned it has a thin coating of the residue of lubricant sometimes mixed with oxides; this coating has a bad effect on the quality of the lamp, especially in gas-filled lamps.

If a lubricant containing graphite is used in drawing tungsten wire, the graphite, owing to the high temperatures inseparable 15 from the drawing process is burnt into the surface of the wire and forms an adherent coating which is very difficult to remove. Up to the present time the wire has usually been cleaned by scouring it for some time in 20 a bath of sand and boiling potash.

The principal object of the present invention is to provide means by which this adherent coating may be easily and quickly removed from drawn wire of the size commonly 25 used in making incandescent lamps.

According to my invention the layer of lubricant is also first loosened by passing the wire through a boiling bath containing a solution of sodium phosphate, potash or caustic soda or mixtures of these solutions. According to the invention the wire is then passed through a scouring device preferably between two or more scouring rolls, turning on axes which make an acute angle with the 30 direction of the wire. These rolls preferably rotate slowly (about three revolutions per minute) in a direction opposite to the movement of the wire and are kept moist by water while the dirty water is led away. The rolls 35 may be provided with scouring surfaces preferably by being covered with chamois-leather, rubber, closely-woven woolen cloth or the like.

In carrying my invention into practice but 40 little force is required for feeding the wire. Moreover the oblique position of the rollers makes the cutting of grooves in their surfaces impossible. No breakage is to be feared, even when fine wires are treated, and the coating 45 is completely removed in a very short time.

In the accompanying drawing one form of the invention is illustrated; numerous improvements and alterations are possible however which would come within the scope of the invention.

Fig. 1 is a front elevation of the apparatus; Fig. 2 is a top-plan view of the two rolls, Fig. 3 shows a modified arrangement of the two rolls, while Figs. 4, 5 and 6 are views on an enlarged scale showing the rolls covered 55 with cloth, rubber and leather respectively.

In Fig. 1 the uncleared wire 1 on the reel 2 is led over pulleys 3, 4 and 5, through a pickling tank 6, containing a hot, and preferably boiling solution of lye, potash or a similar substance, for the purpose of loosening the layer of lubricant.

The wire then passes via a pulley 7 along and against the top of a roll 8, which preferably rotates in a direction opposite to the movement of the wire, and which is kept wet as fully as possible; the wire then rubs against the lower surface of a roll 9, which preferably rotates in a direction opposite to that of roll 8. Both rolls are driven 70 by the same source of power 10, by means of a belt 11 and gears 12 and 13.

The roll 9 is constantly kept wet by pouring liquid onto it out of a nozzle 14, the supply to which can be regulated in any suitable 75 manner. The liquid coming from the roll 9 flows into a flat tank 15, in which the roll 8 rotates and out of which the liquid flows away through an opening in the wall. This manner of moistening the rolls is very advantageous because the roll that takes away the last particles of dirt, is always moistened with fresh liquid.

When the wire leaves roll 9, it passes over a pulley 17 to a reel 18 and is now ready for use. The reel 18 is also driven by the same driving means 10 by means of a belt 19.

The rolls are preferably so positioned that: 80
 1st. The wire does not merely touch the surface of the roll in a single point but is in contact with its surface over a considerable arc (see Fig. 3);
 2nd. The axes of the rolls make an acute angle with the direction of the wire (see Fig. 2). 85

These factors are so chosen, as to make the rubbing surface of the rolls as great as possible. This oblique position also prevents the wire from cutting into the rolls.

- 5 By so positioning the rolls an ideal scouring is obtained, the wire being exposed to a scrubbing operation in the longitudinal direction, a rubbing operation in the transverse direction and a slight rolling movement 10 over the surface of the rolls owing to the fact that it is entrained to a certain extent by these latter.

The wire treated in this manner is much cleaner than the wire previously used, which 15 often has a dull and dead appearance; by the present treatment all traces of the lubricant are removed and the wire has a metallic polished appearance.

Lamps with the wire as heretofore cleaned, 20 give an increase of from 4-10% in lighting power during the first few hours owing to the modifications taking place in the surface of the wire, but lamps made with wire cleaned according to the present invention do not 25 show any perceptible change.

This increase in lighting power of the wire formerly used, was very variable, owing to the varying efficiency of the processes for cleaning the wire from the residues of lubricant.

The wire cleaned in accordance with the present invention is uniform and enables the process of manufacture to be controlled.

The increase of lighting power must be 35 avoided as much as possible, for when a special initial wattage per candle power is adopted and this value changes during burning from 4-10%, a decrease in life of 25-50% is the result.

40 A further advantage of the new invention is that the wire can pass through the apparatus continuously at a velocity of 100-150 metres per minute.

What I claim is:

- 45 1. In a wire cleaning apparatus, the combination with feed mechanism for moving a wire longitudinally along a predetermined path, of a wire scouring device comprising a movable scouring member mounted adjacent 50 the path of the wire to engage the wire, and means for moving said member to cause its scouring surface to move obliquely across the path of and against the direction of movement of the wire.

- 55 2. In a wire cleaning apparatus, the combination with feed mechanism for moving a wire longitudinally along a predetermined path, of a wire scouring device comprising 60 a scouring roll mounted adjacent the path of the wire to engage the wire and to rotate about an axis oblique to said path, and common actuating means for driving said feed mechanism and rotating said roll to cause 65 its surface in contact with the wire to move

across the path of and against the direction of movement of the wire.

3. In a wire cleaning apparatus, the combination with feed mechanism for moving a wire longitudinally along a predetermined path, of a wire scouring device comprising a pair of scouring rolls mounted adjacent to and on opposite sides of the path of movement of the wire to bring them into contact with the wire and to rotate about axes oblique to said path, and actuating means for driving said feed mechanism and rotating said rolls.

4. In a wire cleaning apparatus, the combination with feed mechanism for holding a wire taut and moving it longitudinally along a predetermined path, of a wire scouring device comprising an open tank adjacent and below said path, a scouring roll mounted in position to engage the wire passing over said tank and to turn in the liquid in the tank, a second scouring roll mounted above said tank and adjacent said path to engage the wire, both said rolls being rotatable on axes oblique to said path means for causing a stream of liquid to flow over said second roll into said tank, and common actuating means for driving said feed mechanism to move the wire and simultaneously rotate said rolls.

In witness whereof, I have hereunto signed my name.

ANTONIUS DE GRAAFF.
